United States Patent Office

Des. 179,280

Patented Nov. 27, 1956

179,280

MICRO-PROJECTOR

Olin W. Boughton, Canandaigua, N. Y., assignor to
Bausch & Lomb Optical Company, Rochester, N. Y.,
a corporation of New York

Application May 18, 1956, Serial No. 41,538

Term of patent 14 years

(Cl. D61—1)

FIG. 2

FIG. 1

Fig. 1 is a front perspective view of a micro-projector embodying my new design.

Fig. 2 is a rear perspective view thereof, taken from a lower viewpoint.

The dominant features of my design reside in the portions shown in full lines.

I claim:

The ornamental design for a micro-projector, substantially as shown and described.
